UNITED STATES PATENT OFFICE.

LEONIA MABEE, OF ST. LOUIS, MISSOURI.

DESIGN FOR A SKIRT-PROTECTOR.

SPECIFICATION forming part of Design No. 31,272, dated July 18, 1899.

Application filed March 14, 1899. Serial No. 709,092. Term of patent 14 years.

To all whom it may concern:

Be it known that I, LEONIA MABEE, of the city of St. Louis, State of Missouri, have invented a new and original Design for a Skirt-Protector, of which the following is a full, clear, and exact description, reference being had to the accompanying drawing, forming a part thereof.

In the drawing the figure is a plan view of a skirt-protector, showing my new design, the same being open or unfolded.

As shown in the drawing, the leading or material feature of my design consists of a pair of flexible sections 1 and 2, the lower curved edges 3 thereof being secured together, and the outer corners of each of said members 1 and 2 are cut away, as indicated by 4, and bounding said cut-away portions are the bands 5. Integral with and projecting outwardly from the ends of said bands are the

curved bands 6. The member 1 is slightly wider than is the member 2, and along the edge of said member 1 is formed a plurality of apertures 7.

Appearing upon the inner face of the member 1, between the curved lower edges thereof, is a checkered section 8, and extending inwardly from the cut-away portion 4 of the member 2 is a checkered section 9, the same being bounded by the curved band 10.

I claim—

The design for a skirt-protector, substantially as herein shown and described.

In testimony whereof I affix my signature in presence of two witnesses.

LEONIA MABEE.
